UNITED STATES PATENT OFFICE.

EDWARD WALLACE, OF CLEVELAND, OHIO.

VALVE FOR INTERNAL-COMBUSTION AND FLUID-PRESSURE ENGINES.

1,386,477.

Specification of Letters Patent. Patented Aug. 2, 1921.

Application filed January 8, 1916. Serial No. 71,033.

To all whom it may concern:

Be it known that I, EDWARD WALLACE, a citizen of the United States, residing at Cleveland, in the county of Cuyahoga and State of Ohio, have invented a new and useful Valve for Internal-Combustion and Fluid-Pressure Engines, of which the following is a specification.

My invention relates to improvements in rotary valves for internal combustion and fluid pressure engines in which two or more concentrically arranged valves are arranged to effect the opening and closing of the ports to the combustion chamber of the engine, and has for its object to improve such valves and their method of control and operation as will be hereinafter described.

In the accompanying drawings, in which my invention is illustrated as applied to an internal combustion engine of the four cycle type,—

Figure 1 is a central vertical sectional view through one of the cylinders of the engine.

Fig. 2 is a diagrammatic view illustrating a method of operating the valves.

Fig. 3 is a central vertical section through the cylinder of an engine, illustrating a different embodiment of my invention from that shown in Fig. 1.

Fig. 4 is a similar sectional view showing still another embodiment of the invention.

Fig. 5 is a diagrammatic view illustrating means for operating the valves shown in Fig. 4, and

Fig. 6 is a horizontal sectional view through the valves of the engine illustrated in Fig. 4, parts of the engine frame and valve casing being omitted.

In the drawings I have represented the invention, in several forms, applied to a four cycle internal combustion engine having a crank shaft 1, connecting rod 2, wrist pin 3, piston 4, oil pan 5, cylinder 6 in which works the piston, spark plug hole 7, and water jacket 8 surrounding the cylinder. 9 indicates the inlet valve casing, 10 the exhaust valve casing, these being cylindrical and connected with the cylinder 6 through ports 11 and 12, respectively. They are surrounded by water jackets 13 and 14 which connect with the water jacket 8. Within the inlet valve casing 9 are arranged two concentric sleeve valves, the inner one being designated 15 and the outer one 16, 55 and the latter fitting closely the inner wall of the casing. The sleeve valve 15 is formed with a port 17, and valve 16 with a port 18.

Similar sleeve valves 19 and 20 are located in the exhaust casing, and these are provided respectively with ports 21 and 22. The sleeve valves of each set are turned about their longitudinal axis to cause the ports with which they are provided to register with each other and with the port communicating with the engine cylinder with a frequency required by the cycle on which the engine operates. Various means may be employed for giving the desired movements of the valve sleeves. They may be oscillated or rotated; and if rotated they may be both turned in the same direction or in opposite directions. I prefer that these sleeve valves should be rotated, and that they both turn in the same direction, and in Fig. 2 have indicated, diagrammatically, driving mechanism for effecting such movements. I wish, however, it to be understood that my invention is not limited in its useful applications to the specific mechanism or mechanisms which I have shown for driving the valves.

Referring to Fig. 2, 79 indicates a chain gear wheel on the crank shaft of the engine, connected, through a silent chain 80, with the chain gear wheels 77 and 78, secured respectively to the outer sleeve valves 16 and 20, the gears being so proportioned in size that the sleeve valves are rotated in the ratio of one to two relative to the crank shaft. 83 indicates another chain gear wheel on the crank shaft, connected, by chain 84, with wheels 81 and 82, operating respectively the inner sleeve valves 15 and 19. The size of these gear wheels is such that the sleeve valves are rotated in the ratio of two to one to the crank shaft. It will be observed that the four sleeve valves that have been referred to are, through the driving gear described, all rotated in the same direction; and that their ratios of rotation are such that the ports in the valves 15 and 19 register with the ports communicating with the engine cylinder four times as often as the valve of a four-cycle engine of ordinary type is caused to operate, but that only every fourth registration between such ports is effective, since not only must the ports in the valves 15 and 19 register with the ports leading to the engine cylinder, but they must simultaneously register with the ports in the valve sleeves 16 and 20.

In combination with the inlet and exhaust valves described are combined means for advancing and receding the valve registering

periods relative to the crank angle of the crank shaft of the engine. One form of such mechanism is shown in Fig. 1, where 73, 74 designate a pair of timing sleeves fitting between the inlet valves 15, 16, and concentric therewith. These timing sleeves are provided respectively with ports 113 and 114, adapted to be brought into position to register with the ports leading to the engine cylinder, and with the ports in the inlet valves when they register with each other and with the engine port. The timing sleeves are supported so they may be independently turned about their common axis and are provided with adjusting means, that I will presently describe, so that a universal timing, that may be altered and then fixed, may be obtained. The adjustment may be hand controlled, or automatic and controlled by a governor, and such that the most effective timing of the opening and closing of the engine ports for every speed of the engine may be had while the engine speed is either varied or constant. It permits of the mutual adjustment of the timing mechanisms for any size of engine or for any kind of fuel that may be used.

The adjusting mechanism for the timing sleeves shown in Fig. 1 will now be described, such mechanism being adapted to adjust the two sleeves relative to each other, by respectively oscillating them about their common axis, and also to adjust the two sleeves as a unit relative to the port 11 leading to the engine cylinder. To effect the adjustment of the timing sleeves relative to each other I provide the sleeves 73 and 74 respectively with arms 88 and 91 that are connected, by links 87 and 90, with the two arms, 86 and 89, of a double bell crank lever supported upon a fulcrum 93, the third arm of which bell crank lever is designated 85. By operating the bell crank lever, through the arm 85, the timing sleeves will be shifted, one in one direction and the other in the other, as will be apparent. The fulcrum 93 is carried at the end of a bell crank lever 92 fulcrumed on a support 94 carried by a bracket or lug 95 projecting from some part of the engine. By shifting the bell crank lever 92 the two timing sleeves, whatever be their positions relative to each other, will be adjusted together or as a unit and relative to the port 11.

Combined with the exhaust valves 19 and 20 are adjustable timing sleeves 75 and 76 similar in construction and arrangement with the timing sleeves 73 and 74 for the inlet valve. The exhaust valve timing sleeves 60 are operated by mechanism similar to that which has been described for operating the other set of timing sleeves. The arms that project from the timing sleeves for the exhaust valves are designated 99 and 102. The links that unite these arms with the double

bell crank lever are designated 98 and 101, the arms of the double bell crank lever are designated 96, 97 and 100, and the fulcrum upon which this lever is mounted 104. The bell crank lever carrying the fulcrum 104 is 70 103, and it is supported upon a fulcrum 105 carried by a bracket or lug 106.

The two sets of timing sleeves, that is, those for the inlet valves and those for the exhaust valves, should ordinarily be 75 simultaneously adjusted. This I effect by connecting the arms 85 and 96 of the double arm bell crank levers by means of a link 107, and by connecting the operating arms of the bell crank levers 92 and 103 by means 80 of a link 108. The connections between the links 107 and 108 and the adjusting levers which they unite are adjustable, one or both of each set of the united parts being slotted for the passage of the adjustable connecting 85 bolt or pin, as shown in the drawings. This arrangement permits the individual timing sleeves for each valve to be independently adjusted relative to each other and then set and connected so that the desired adjustments may be maintained. So, too, each set of timing devices may be independently adjusted relative to the ports leading to the engine cylinder after which they may be set and connected. The ends of the connecting links 107 and 108 are constructed 95 to be connected with adjusting mechanism, such as a hand lever or connecting rod operated by an automatic governor, the ends of such links nearest the inlet valve being, 100 in Fig. 1, represented as formed for such connection.

The adjustable timing sleeves 74 and 76 are provided respectively with lugs 109 and 110 that extend into the ports 113, 115, of 105 the timing sleeves 73 and 75. When the timing sleeves are adjusted so as to bring their ports,—113, 114, for the inlet valve timing sleeves, and 115, 116, for the outlet valve timing sleeves,—into coincident registration, the lugs 109 and 110 will be in engagement with the sleeves 73 and 75, at points beyond the spaces 111, 112, Fig. 1, whereby further relative movement of these sleeves is prevented. This is a ready means 115 for determining the coincident registration of the ports in the timing sleeves.

In Fig. 3 I have shown a different form of the engine, more simple in construction than that shown in Fig. 1 and already described, in which I provide adjusting means for advancing and receding the valve registration periods relative to the crank angle of the crank shaft of the engine. The valve registration period for each valve, inlet and 120 exhaust, may be independently varied and also the adjusting means may be connected for effecting simultaneous movement of the valve adjusting means.

The sleeve valves 15 and 19 are caused to 130

revolve by the following means. 68 is a chain gear wheel on the engine crank shaft, connected by a chain 72 with a wheel 69 connected with the sleeve valve 19 so as to rotate it. The gear wheels 68 and 69 are of such sizes that the latter is driven in the ratio of one to two to the engine crank shaft. Another gear 70 is also carried by the sleeve valve 19, and this is in mesh with 10 and drives a gear wheel 71 of the same size, carried by the inlet sleeve valve 15.

The outer sleeve valves 16 and 20 are adjustable, relative to the valves 15 and 19 but are not rotated when the engine is in operation. They are provided, respectively, with arms 65 and 66 connected by a link 67. The connections between this link and the arms are such as to permit relative independent adjustment of the arms one or both 20 members of each connection being slotted as indicated in the drawings. By loosening the connections just referred to the sleeves 16 and 20, which are timing sleeves, may be independently adjusted and then set by 25 tightening the connections with the connecting link 67. When the engine is in operation the timing sleeves, after having been adjusted to cause the desired registration respectively between the inlet and outlet 30 valve chambers and the engine cylinder, may be held in fixed position, or they may be oscillated in order to insure a more rapid or a slower opening and closing of the ports through the valves, as may be desired; for it 35 will be understood that by making one of the sleeves a timing or governing sleeve, and oscillating it to vary the timing of the valve and to increase or diminish the angle of the valve port opening, the advantage of variable timing by advancing or receding the 40 valve registering period is attained.

In Figs. 4, 5 and 6 I show an arrangement in which the sleeve valves 15, 16 and 19, 20, are rotated and where there are, arranged 45 between these valves, variable timing or governing valves in the form of sleeve segments. The variable governing means associated with the rotating inlet valves are designated 117, 118, while those associated with 50 the exhaust valves are designated 119, 120.

In the embodiment of my invention illustrated in these views I show a different arrangement for rotating the sleeve valves from that illustrated in any of the other 55 views. Referring to Figs. 5 and 6, 121 indicates a gear on the engine crank shaft, driving, through a chain 123, a gear 122 on shaft 125. This shaft carries a gear 124 that in turn drives gears 126, 127, respectively 60 secured to the outlet sleeve valves 16 and 20.

The gear 124 also drives intermediate or idler gears 128 and 129, and these respectively drive gears 130, 131 secured to the inner sleeve valves 15 and 19. By this arrangement of gearing the concentric sleeve

valves of each set are turned in opposite directions and the ratios of their rotations to that of the crank shaft of the engine are determined by the cycle on which the engine works and controlled by the relative sizes 70 of the gears in the train described, as will be understood by those familiar with engine construction. The means for controlling the ports of the inlet and exhaust valves and for varying their positions for advancing or receding the valve registering periods are, as have been stated, a pair of segments for each valve arranged between the concentric pair of rotating sleeve valves. The two segments of each valve may together 80 be considered an adjustable governing or timing valve with a port adapted to register with the ports of the sleeve valves with which such governing and timing device is used, this port being the space between adjacent edges of the segments. The segments are independently adjustable about the axis common to the valve of which they constitute a part. The two segments may be moved toward each other so as to decrease 90 the size of the port through this adjustable valve, or separated to enlarge that port, or the two segments may be correspondingly moved either in one direction or the other between the two rotatable sleeve valves in 95 order to advance or recede the registration period between the valve ports and the port to the engine cylinder. Referring for the moment to the inlet valve, represented in Figs. 4 and 6, it will be seen that the sleeve segments 117 and 118 are connected with the outer sleeve valve 16 so as to be rotated thereby. To effect this the sleeve valve 16 is provided with pins 132, 132' and 133, 133', these being arranged, preferably, diametrically opposite to each other. The pins project inwardly and lie in inclined slots, 134, 134', and 135, 135', formed respectively in the sleeve segments 117, 118. The sleeve segments are not only rotatable with the sleeve 100 valve 116, but are also each longitudinally movable as a whole; and since the slots in the sleeve segments are inclined to the center lines respectively of the sleeves, any longitudinal movement of a segment will 105 cause it to be shifted about the central axis of the valve considered as a whole, and such shifting of the segment moves its edge either toward or from the opposite edge of the other segment. To effect this longitudinal movement of the adjustable segments 117, 118, any suitable mechanism may be employed, for instance, that illustrated in Fig. 6, where 142 indicates a shaft on which

are supported two concentric, longitudinal 110 movable, sleeves 141, 145 carrying grooved collars 143, 146. The outer ends of the adjustable segments are turned inwardly and lie in the grooves formed in the said collars. 115 This form of connection allows the sleeves 120 secured to the outer sleeve valve 16 to be rotated and the sleeves 117, 118 to be moved longitudinally. Referring to Fig. 5, 121 indicates a gear on the engine crank shaft, driving, through a chain 123, a gear 122 on shaft 125. This shaft carries a gear 124 that in turn drives gears 126, 127, respectively 125 secured to the outlet sleeve valves 16 and 20. The gear 124 also drives intermediate or idler gears 128 and 129, and these respectively drive gears 130, 131 secured to the inner sleeve valves 15 and 19. By this arrangement of gearing the concentric sleeve

to turn freely to whatever position, longitudinally, they may be adjusted. Bell crank levers 140, 144 are connected respectively with the sleeves 141 and 145 and serve as 5 the means by which such sleeves may be adjusted along the shaft 142.

The ends 149, 150 of the inner sleeve valves 15 and 19, respectively, are closed and their opposite ends are connected to the 10 intake and exhaust pipes of the engine, the showing of the latter being deemed unnecessary.

The adjustable governing and timing devices for the exhaust valve are similar to 15 those that have just been described for the inlet valve. The adjustable segments for this valve are designated, respectively, 119, 120. They are connected with the outer sleeve valve 20 by pins 136, 136' and 137, 20 137' which, respectively, lie in slots 138, 138' and 139, 139' in the sleeve segments. The sleeve segments 119, 120 are moved longitudinally by means of bell crank levers 147, 148. The bell crank levers 140, 147 and 144, 25 148 may be, respectively, united by connecting links similar to those indicated in Figs. 1 and 3, so that the valves after being once properly adjusted may be maintained in adjusted position, and whereby also the correspondingly adjustable parts of the inlet and 30 outlet valves may be simultaneously and correspondingly moved.

The several illustrations of my invention 35 serve to show that the means for operating the valves may be varied without departing from the invention herein presented, and that the means for timing the port openings and for advancing or receding the valve registering periods may also be varied, without departing from the invention.

I claim—

1. The combination with an engine cylinder, of a valve mechanism comprising a casting with a curved seat and connected with 45 the engine cylinder by a port, a pair of curved valves concentrically arranged in the said casing, the valves having ports, means for moving the valves to cause their ports to register with each other and with the port 50 leading to the engine cylinder with a frequency required by the cycle on which the engine operates, and an adjustable curved valve mounted between the said movable valves and arranged to vary the effective 55 size of the opening to the engine cylinder, the latter valve being normally stationary, and means for adjusting the said normally stationary valve.

2. The combination with an engine cylinder, of a valve mechanism comprising a casting with a curved seat and connected with the engine cylinder by a port, a pair of sleeve valves concentrically arranged in the said casing, the valves having ports adapted 60 to register with each other and with the 65

port leading to the engine cylinder, and a pair of curved normally stationary valves located between the said movable valves and movable with reference to each other to vary the effective size of the opening to the 70 engine cylinder, and means for adjusting the said normally stationary valves.

3. The combination with an engine cylinder, of an inlet valve mechanism therefor, an exhaust valve mechanism therefor, means 75 for operating these valve mechanisms with a frequency required by the cycle on which the engine operates, a supplemental valve for each valve mechanism arranged to vary the timing at which the valve mechanisms 80 respectively operate, and means for uniting these supplemental valves to cause them to operate simultaneously.

4. The combination with an engine cylinder, of an inlet valve mechanism therefor, 85 an exhaust valve mechanism therefor, means for operating these valve mechanisms with a frequency required by the cycle on which the engine operates, a supplemental valve for each valve mechanism arranged to vary 90 the timing at which the valve mechanisms respectively operate, means for adjusting the supplemental valves independently of each other, and means for uniting them whereby after adjustment they may be 95 moved and adjusted simultaneously.

5. The combination with an engine cylinder, of an inlet valve mechanism therefor, an exhaust valve mechanism therefor, means 100 for operating these valve mechanisms with a frequency required by the cycle on which the engine operates, means by which the said valves may be adjusted independently to vary the effective sizes respectively of the inlet and exhaust openings to the engine cylinder, and means for uniting the said supplemental valves whereby after adjustment 105 they are caused to move together.

6. The combination with an engine cylinder, of an inlet valve mechanism therefor, 110 an exhaust valve mechanism therefor, means for operating these valve mechanisms with a frequency required by the cycle on which the engine operates, a supplemental valve device for each valve mechanism, comprising a pair of curved valves movable with reference to each other and arranged when adjusted relatively to more or less cover respectively the inlet and exhaust openings to the cylinder, means for adjusting the said 115 supplemental valves as stated, and means for adjusting each of the supplemental valve devices to vary the timing of admission and exhaust.

In testimony whereof I hereunto affix my 125 signature in the presence of two witnesses.

EDWARD WALLACE.
